P. F. DANIEL.
VALVE FOR INTERNAL COMBUSTION AND OTHER ENGINES.
APPLICATION FILED NOV. 18, 1919,

1,414,341.

Patented May 2, 1922.

UNITED STATES PATENT OFFICE.

PETER FRANCIS DANIEL, OF CHRISTCHURCH, NEW ZEALAND.

VALVE FOR INTERNAL-COMBUSTION AND OTHER ENGINES.

1,414,341.

Specification of Letters Patent.

Patented May 2, 1922.

Application filed November 18, 1919. Serial No. 338,787.

To all whom it may concern:

Be it known that I, PETER FRANCIS DANIEL, a subject of the King of Great Britain, residing at Royal Exchange Buildings, Cathedral Square, Christchurch, New Zealand, have invented new and useful Improvements in and Relating to Valves for Internal-Combustion and Other Engines, of which the following is a specification.

- 10 This invention relates to valves for controlling the admission and exhaust in internal combustion and other engines and refers to that type of valve comprising a revolving member or rotor in which are provided openings or ports adapted at the required stage in the cycle of the engine to register with stationary ports and so provide the necessary communication between the cylinder and the induction or exhaust pipes.
- 15 20 In cases where a rotor of this nature has been employed to co-act with a plurality of ports, as for instance in the case of an engine having two or more cylinders, difficulty has been experienced in providing and maintaining the degree of gas-tightness between the rotor and the several port-faces necessary to obtain a satisfactory compression of the gas within the cylinders.

It is the object of the present invention 30 therefore to overcome this difficulty by providing a construction whereby an individual adjustment of the rotor in relation to each of the port-faces may be effected, while a further object of the present invention 35 is to provide a construction of this nature in which a circulation of water may be maintained through the rotor for cooling purposes.

In carrying these objects into effect the 40 present invention consists essentially of constructing the rotor in the form of a series of sections disposed at the desired intervals apart and conjoined end-to-end by means of axially disposed flexible connections having 45 hollow cores adapted to permit of the flow of a circulation of water therethrough and through hollow cores provided in said sections.

In order that the nature of the invention 50 may be clearly understood, reference will now be made to the accompanying drawings in which;—

Figure 1. shows three valves constructed in accordance with the present invention, 55 Figure 2. is a sectional elevation showing

two cylinders of an engine fitted with valves in accordance with the present invention,

Figure 3. is a cross-section along the line A—B Figure 2, and,

Figure 4. is a plan view showing the inlet 60 and exhaust valves of two cylinders illustrating by way of example, an alternative method of driving for that employed in the preceding figures.

As here shown the valves are arranged in 65 the "overhead" position in relation to the cylinders and such valves consist of twin rotors one to control the inlet and the other to control the exhaust.

It will be understood, however, that the 70 valves may, if preferred, be arranged upon the side or any other suitable position upon the cylinders and similarly such valves may, if desired, be included in the form of a single rotor.

According to the present invention the 75 rotor takes the form of a series of sections 1 disposed at the desired intervals apart and conjoined end-to-end by means of axially disposed flexible connections 2 having hollow 80 cores 3 adapted to permit of the flow of a circulation of water therethrough and through hollow cores 4 formed in the said sections 1.

These flexible connections 2 consist pref- 85 erably of lengths of spirally constructed flexible metallic tubing which are suitably attached as by clamping, brazing, or other means, to the said sections.

In lieu of this construction however, the 90 flexible connections may consist of ball and socket joints or any other suitable or appropriate flexible means of communication between such sections and adapted to provide the necessary passage for water to circulate 95 through the said hollow cores 4.

The said flexible connections whether of the spiral tubular form or otherwise, are preferably so constructed as to withstand the necessary torsional strain involved in turning 100 the rotors and transmitting the drive from one section to the other.

If necessary however, additional mechanical means may be provided to relieve the 105 flexible connections of this torsional strain but without impairing the necessary flexibility between such sections.

As here shown, in Figures 1 and 2, this purpose is effected by the employment of couplings 5 attached to the ends of the sections 110

1 by screws 6 or other suitable means or again such couplings may be formed integral with the rotor sections. The said couplings 5 terminate at their outer ends in 5 dog-clutches or teeth or other formations 7, adapted to interlock as here shown.

In cases where clutches 5 are employed and attached to the sections 1 the ends of the flexible connections 2 may be received within 10 close-fitting sockets 8 provided in spigots or bosses 9 and the necessary water-tight joints between the connections and the sections 1 may be provided by inserting suitable packing 10 between the ends of the 15 spigots 9 and the corresponding portions of the couplings, as here shown in Figure 2.

In lieu of the couplings however, the driving of the various sections, in the case of either a single or twin rotor construction, 20 may be effected (as shown in Figure 4) by the employment of a shaft 11 disposed parallel with the rotor or rotors and upon which shaft are keyed, at the required positions upon the length thereof, gear wheels or the 25 equivalent 12 adapted to intermesh with gear wheels or the like 13 keyed upon or formed integral with the various sections 1.

It must be clearly understood however, that the foregoing means for mechanically 30 operating the sections are given merely by way of example and the invention must not therefore be confined thereto or indeed to the use of mechanical means of any kind as such means are only necessary, as already 35 pointed out, in cases where the flexible connections are of such a nature as to be incapable of withstanding the torsional strain, and preserving correct relationship of the various sections 1 to each other.

40 The mounting of the valve consists of a series of suitably formed and fixed seats or port-faces 14 containing the usual ports 15 communicating with the cylinders 16, and a corresponding series of port-faces 17 containing ports 18 communicating with the induction pipe 19 or exhaust pipe 20, as the case may be, such ports being placed in communication by the registering therewith of the ports 21 of the rotor as customary.

50 According to the present invention for the purpose of keeping the various sections of the rotor in close and gas-tight contact with the seats or port-faces 14, the port-faces 17 are made adjustable.

55 As here shown (Figures 2 and 3) this purpose is effected by mounting such port-faces 17 slidably in caps 22 which latter are secured to the portion of the engine containing the port-faces 14 by means of studs, 60 bolts or other suitable means 23.

Mounted upon the upper or outer extremities of the caps 22 are the induction and exhaust manifold pipes 19 and 20 which are clamped in place by studs 24 or other suitable means.

For the purpose of causing the adjustable port-faces 17 to exert the desired degree of pressure upon the rotor sections to keep the latter in gas-tight contact with the port-faces 14, as already mentioned, springs 25 70 are inserted between the port-faces 17 and the exhaust or induction pipe 19 or 20.

To convey the explosive mixture or exhaust gas past the springs 25 the port-faces 17 are provided with extensions or shrouds 75 26 slidably received within suitable openings provided in the said induction or exhaust pipes, as clearly shown in Figures 2 and 3.

This construction is however, shown merely by way of example and this feature of the 80 invention must not therefore, be confined thereto but includes within its scope the employment of any suitable port-faces adapted to be adjusted by means of springs, set-screws or other means so as to cause their 85 corresponding rotor-sections to bear with the desired degree of pressure upon their seats or fixed port-faces as already mentioned.

For the purpose of lubricating the rotor-sections in order to obviate the danger of 90 seizing and to reduce friction, a layer of felt or other absorbent material 27 is arranged in a suitable recess in the central portion of each of the caps 22 in such a manner that the ends of such felt will be in wiping 95 contact with the peripheries of the rotor-sections and a suitable pipe or duct 28 is provided to supply oil to the felt 27.

It will be understood that, in consequence of the flexibility provided in the joints between the rotor-sections, it will by this construction be possible to make an individual adjustment in each case so as to cause each section to bear with the desired degree of pressure against its respective fixed port-faces upon the cylinder. 105

The said sections may be so arranged that each will contain one of the said port openings adapted to come into and out of register with the stationary ports or if so desired 110 each of such sections may be arranged to contain two or more of such port openings.

I claim.

In a rotary valve the combination of a series of port-faces, a ported rotor adapted 115 to co-act therewith and consisting of a series of sections conjoined end-to-end by flexible connections adapted to permit the flow of a circulation of water therethrough and through hollow cores in said rotor sections, 120 and means for transmitting the necessary drives to said sections and for relieving said flexible connections of torsional strain.

In testimony whereof I have signed my name to this specification.

PETER FRANCIS DANIEL.
